DESIGN FOR A TYPEWRITING MACHINE

Lawrence E. Lentz, New Canaan, Conn., assignor
to Underwood Elliott Fisher Company, New
York, N. Y., a corporation of Delaware

Application January 20, 1942, Serial No. 105,337

Term of patent 14 years

To all whom it may concern:

Be it known that I, Lawrence E. Lentz, a citizen of the United States, residing in New Canaan, in the county of Fairfield and State of Connecticut, have invented a new, original, and ornamental Design for a Typewriting Machine, of which the following is a specification, reference being had to the accompanying drawing, forming part thereof.

The figure is a perspective view of a typewriting machine, showing the new design.

The dominant features of my design reside in the portion of the machine shown in solid lines on the drawing.

I claim:

The ornamental design for a typewriting machine, as shown and described.

LAWRENCE E. LENTZ.
